COMBINED SPEAKER ENCLOSURE, TELEVISION AND RADIO CABINET

Alexander Rauchman, New York, N. Y.

Application March 5, 1954, Serial No. 29,376

Term of patent 7 years

(Cl. D56—4)

Fig. 6

Fig. 5

To all whom it may concern:

Be it known that I, Alexander Rauchman, a citizen of the United States, residing in the county of New York and State of New York, have invented a new, original, and ornamental Design for a combined Speaker Enclosure, Television and Radio Cabinet, of which the following is a specification, reference being had to the accompanying drawings, forming part thereof.

Fig. 1 is a front elevational view showing my new design for a combined speaker enclosure, television and radio cabinet.

Fig. 2 is an enlarged detailed front view of the handle portion thereof.

Fig. 3 is a top plan view of Fig. 2.

Fig. 4 is a vertical sectional view of Fig. 2.

Fig. 5 is another front view with door in open position. Fig. 6 is a sectional view taken on line 6—6 of Fig. 5. The top, sides, and rear of the cabinet are plain and of conventional configuration.

I claim:

The ornamental design for a combined speaker enclosure, television and radio cabinet, as shown and described.
